UNITED STATES PATENT OFFICE.

RICHARD F. HALLADAY, OF LEOMINSTER, MASSACHUSETTS.

RENEWABLE BUTTONING DEVICE.

1,208,148.

Specification of Letters Patent. Patented Dec. 12, 1916.

Application filed March 23, 1916. Serial No. 85,861.

To all whom it may concern:

Be it known that I, RICHARD F. HALLADAY, a citizen of the United States, residing at Leominster, in the county of Worcester 5 and State of Massachusetts, have invented a new and useful Renewable Buttoning Device, of which the following is a specification.

This invention relates to a buttoning device suitable for use on boys' pants and other garments.

The principal objects of the invention are to provide a member carrying a plurality of button-holes or buttons which can be moved 15 for the purpose of presenting a new button-hole or button to operative position; to provide a simple device for this purpose and one which can be changed readily and without detaching the device or sewing it in 20 position; also to provide improvements in details of construction.

Reference is to be had in the accompanying drawings in which—

Figure 1 is a front view of a boy's pants 25 with a preferred embodiment of this invention applied thereto; showing the waist to which the pants are to be buttoned, and a button thereon spaced above the top of the pants. Fig. 2 is an elevation of the button-hole attachment, and Fig. 3 is a sectional view of the same on the line 3—3 of Fig. 2.

The invention is shown in a form in which the garment, as for example a pair of pants 9, is provided with a member 10, preferably 30 circular in form, and having a center at which it is attached to the garment. Preferably this attachment is in the form of a snap fastener 11, made in two parts, one secured permanently to the member 10 and 35 the other to the garment 9, so that the whole device can be taken off and put back on in a different position. But other means for fastening it may be used so long as it is capable of turning on the center. In the form shown 40 this member consists of two sheets of cloth sewed together around the edge and also having radial rows of stitches 12 dividing it into pockets. There is shown also a circular line of stitches just outside of the snap fastener to which these rows of stitches 12 extend. This divides the circle up into a number of segments, four being shown in the drawings. In each of these segments is arranged a buttoning device, shown as a button-hole 13. These button-holes are arranged radially, that is, they stand directly 45 in line with the center of the device and each one is practically located at the middle of its pocket so that it is bound by the line of stitching outlining the pocket. 50

It will be understood that although I have described the form of the invention shown in the drawings as formed of two thicknesses of cloth yet some other material can be used, as a single thickness of leather 55 may be substituted for it. In either case, it is preferred to stiffen the device by the use of thin pieces or strips of celluloid 14 or some similar material. These are secured to the cloth or leather throughout their lengths 60 and keep the device spread out straight so that it will not wrinkle up in practice or roll up. In some cases the buttoning device can be represented by buttons instead of button-holes. 65

In the use of the device the snap fastener or other fastening device is secured in position so as to hold the member 10 with one button-hole in vertical position or extending 70 from the center in a line toward the line of pull, if it is not used vertically. In the drawings the upper button hole 13 is intended to receive the button 16 on a supporting waist 15. In this way the strain on the parts comes directly toward the center 75 in this case. When the button-hole becomes worn or damaged the device can be turned to another position without detachment and thus an entirely fresh button-hole is brought 80 into position. Furthermore, when this is 85 done the line of strain on the center of the cloth changes and therefore any tendency to breaking out that may have been induced by the strain in the first case will not act to materially weaken the fastening in the second case. 90 It will be understood, however, that with the snap fastener of the ordinary kind the area within which it is secured to the cloth or leather is comparatively large 95 so that there is no one point at which the strain comes. In other words the snap fastener itself strengthens the material at the center. 100

It will be seen that with this device the durability of a garment can be very greatly 105 extended by the addition of very small expense in its manufacture. It is a well known fact, particularly in the case of boys' pants and especially the cheaper grades, that the life of the garment is limited by 110 the durability of the strip having the button-holes. As this is usually made of very

cheap cloth the garment has to be thrown away before it is really worn out or else considerable work has to be done on it. By the use of this invention whether in the 5 form shown or otherwise, each of the buttonholes can be replaced by one of these members and these can be furnished by the manufacturer or applied in the household after the garment is bought. In the latter 10 case, they will ordinarily be sewed on instead of being fastened by snap fasteners or the like, but in any case it is a simple matter to turn them around and present a fresh button-hole. It will also be seen that there is 15 absolutely no wear on the button-holes that are not being used nor the material on which they are located.

Although I have illustrated and described 20 only a single form of the invention I am aware of the fact that many modifications can be made therein by any person skilled in the art without departing from the scope of the invention as expressed in the claims, therefore, I do not wish to be limited to all 25 the details of construction herein disclosed, but

What I do claim is—

1. As an article of manufacture, a garment having a member thereon provided 30 with a plurality of button-holes, said member being fastened to the garment at a point and being capable of being turned about said point to a plurality of positions, in each of which one of said button-holes is lo-

cated in operative position, without being 35 detached from the garment.

2. As an article of manufacture, a garment provided with a member secured thereto at its center and capable of being turned on said center to different positions and having a plurality of buttoning devices radiating from said center. 40

3. As an article of manufacture, a garment provided with a circular member of sheet material secured to the garment at the 45 center of the member, capable of turning on said center, and having a plurality of button-holes arranged around the center.

4. The combination with a garment, of a member formed of sheet material, a snap 50 fastener having two parts, one mounted on said member and one on the garment adapted to be snapped together to secure the member to the garment at any desired angle, said member being provided with button-holes arranged around said fastener. 55

5. As an article of manufacture, a button-hole member consisting of two sheets of cloth in circular form sewed together 60 around their edges and provided with radiating rows of stitching equally spaced apart to form a series of pockets in the member, button-holes arranged in each of said pockets, and fastening means located at the center. 65

In testimony whereof I have hereunto set my hand.

RICHARD F. HALLADAY.
